UNITED STATES PATENT OFFICE.

LEO STEWART WEST, OF WASHINGTON, DISTRICT OF COLUMBIA, ASSIGNOR OF ONE-HALF TO LEON D. BUNDARA, OF PHILADELPHIA, PENNSYLVANIA.

COMB.

1,323,136.

Specification of Letters Patent.

Patented Nov. 25, 1919.

Application filed September 22, 1917. Serial No. 192,721.

To all whom it may concern:

Be it known that I, LEO STEWART WEST, a citizen of the United States, residing at the city of Washington, District of Columbia, have invented new and useful Improvements in Combs, of which the following is a specification.

This invention relates to an improvement in combs, more particularly adapted to drying, and removing the kinks from hair.

An object of the invention is to provide a comb with a row of stationary teeth, and a row of movable teeth, the movable teeth being arranged in alinement with the stationary teeth and the movable teeth and stationary teeth being alternately arranged; the said movable and stationary teeth having work engaging faces which are normally spaced apart, and means for causing the movable teeth to be moved toward the stationary teeth, whereby the operating faces of the teeth may be brought together for treating the hair.

A further object of the invention is to provide means for heating the teeth, whereby they may be heated during the treatment of the hair or prior to the treatment.

The invention consists of certain novel features of construction and combinations of parts which will be hereinafter described and pointed out in the claims.

In the accompanying drawings—

Figure 1 is a view in side elevation of the invention;

Fig. 2 is a top plan view, with the handle broken away, and shown in section;

Fig. 2^a, is a detail top plan view;

Fig. 3 is a longitudinal vertical sectional view;

Fig. 4 is a bottom plan view with the handle broken away;

Fig. 5 is a transverse vertical sectional view;

Fig. 6 is a perspective view of the movable toothed member;

Fig. 7 is a detail view partly in elevation and partly in section, showing an electric heating coil for heating the comb; and

Fig. 8 is a top plan view.

The head 1 of the comb is preferably made hollow, and is provided with teeth 2, 2 integrally connected thereto, one face of each tooth being rounded as at 3.

Slots 4, 4 are formed in the bottom of

the head between the teeth 2, for the reception of movable teeth 5, 5 carried by a bar 6. The teeth 5 are provided with a rounded face 7, the rounded face 7 of the movable teeth 5 and the rounded faces of the stationary teeth 2 are adapted to be brought together when the hair is to be treated, thereby presenting a smooth rounded surface to the hair, so that there is no danger of the hair being injured during the treatment.

A tubular member or extension 8 is removably connected to the head 1, and mounted on the extension is a hollow handle 9. A tube or rod 10 is received in the handle 9 and extension 8. The bar 6 of the movable teeth 5, is provided with two ears 11, provided with holes through which the tube 10 extends, one of the ears being provided with screw threads which engage the screw threads 12 on the tube 10 for fastening the movable toothed bar 6 to the tube. The tube is closed at its outer end, and projects through an opening 13 in the end of the head for guiding the same in its movements. A spring 14 surrounds the tube, and is located between the innermost ear 11 of the toothed bar 6 and the inner end of the head 1, for normally forcing the movable teeth out of engagement with the stationary teeth, that is, the working or rounded faces of the teeth of the movable and stationary teeth from engagement when the comb is not in use.

The tube 10 is provided with openings 15 at its outer end through which gas may issue, and be ignited for heating the comb, a Bunsen burner being provided at the inner end of the tube, where it is connected to a tubing (not shown) for attaching it to a gas supply.

Located at the forward end of the handle 9 is an operating or finger lever 16, which is connected to a bar 17, extending parallel with the tube 10, and into a recess 18 in the handle. A right angular extension 19 is formed on the bar and is provided with an opening through which the tube 10 extends, the extension 19 being adapted to engage a collar or shoulder 20 formed on the tube 10 for reciprocating the tube, for causing the teeth to be brought into engagement with the stationary teeth 2, as the finger lever is drawn rearwardly.

A cover 21 is slidably fitted in the top of

the head 1, and is provided with openings 22 for the discharge of the products of combustion. Holes 23 are formed in the side walls of the head 1 to admit air to assist in the combustion of the gas.

5 In Figs. 7 and 8, an electric heating coil 24 is shown fitted within the head 1, and to which a socket 25 is connected by a cord 26. The coil is preferably proportioned so 10 as to prevent overheating.

When the comb is to be used, it is either attached to a gas supply, or an electric supply, and the teeth heated, and after the teeth have become sufficiently heated, the gas or 15 electricity may be cut off as desired. The comb is now inserted in the hair, and the finger lever 16 is operated causing the rounded or engaging faces of the teeth 2 and 5 to be brought together and engage the 20 hair therebetween, when the comb is drawn outwardly allowing the hair to be drawn between the teeth, for drying and straightening the hair. This operation is simple and can be repeated until the hair is in the condition desired, without danger of breaking 25 the hair. Upon releasing the finger lever 16, the spring 14 will cause the movable teeth 5 to assume their original position.

What I claim as my invention is:—

30 1. In a comb, the combination of a head having a row of teeth thereon and a row of movable teeth supported on the head, said movable teeth and first mentioned teeth being alternately arranged, each of said teeth 35 having a rounded face, the rounded faces of the movable teeth being adapted to co-operate with the rounded faces of the other teeth in treating the hair, and means for operating the movable teeth.

40 2. In a comb, the combination of a head having teeth thereon, a movable bar provided with a plurality of teeth received in

the head, said last mentioned teeth adapted to be located in alinement with the teeth of the head, a hollow handle connected to said 45 head, and means slidale in said handle and connected to the movable bar for operating the teeth.

3. In a comb, the combination of a head having teeth thereon, a movable bar provided with a plurality of teeth received in the head, said last mentioned teeth adapted to be located in alinement with the teeth of the head, a hollow handle connected to said 50 head, means slidale in said handle and connected to the movable bar for operating the teeth, and means carried by the head for 55 heating the teeth.

4. In a comb, the combination with a head having teeth thereon, a plurality of 60 movable teeth supported on the head, and a heating member connected to the movable teeth for heating the teeth, and for moving the teeth.

5. In a comb, the combination with a 65 head having teeth thereon, a plurality of movable teeth supported on the head, and a movable heating tube connected to the movable teeth for heating the teeth and for causing the movable teeth to be operated. 70

6. In a comb, the combination of a hollow head having a row of stationary teeth and slots formed therein between the teeth, a bar provided with a plurality of teeth received in the head, said last mentioned teeth 75 passing through the slots in the head and located in alinement with the teeth of the head, and a heating element removably connected to the bar for heating the teeth on the bar and head, and for moving the teeth 80 of the bar into engagement with the teeth of the head.

LEO STEWART WEST.
